UNITED STATES PATENT OFFICE.

HENRY FRANCIS KEIL, OF BRONXVILLE, NEW YORK.

BRACKET.

No. 813,501.

Specification of Letters Patent.

Patented Feb. 27, 1906.

Application filed May 27, 1904. Serial No. 210,144.

To all whom it may concern:

Be it known that I, HENRY FRANCIS KEIL, a citizen of the United States of America, and a resident of Bronxville, in the county of 5 Westchester and State of New York, have invented a certain new and useful Bracket, of which the following is a specification, the same being a full, clear, and exact description of the invention, such as will enable others 10 skilled in the art to which it appertains to make and use the same.

My invention relates to articles constructed and arranged to serve as supporting plates or arms and provided with means to sustain 15 shelves, &c., and also having engaging means whereby the same may be secured to a suitable back bar, channel-plate, or other support; and it has for its object the production of a structure formed of sheet metal and stamped 20 out in order to provide a light as well as strong and durable, although inexpensive, metal bracket.

With this object in view the invention consists in certain novel features of construction 25 and combination and arrangement of parts, all of which will be hereinafter described, and specifically pointed out in the drawings which accompany and form a part of this specification, in which—

30 Figure 1 represents a side elevation of a bracket and support constructed according to my invention. Fig. 2 is a plan view of the same. Fig. 3 is a view in section, taken on the line 3 3, Fig. 2. Fig. 4 is a view in section, taken on the line 4 4, Fig. 1. Fig. 5 is a side elevation of a bracket embodying my invention. Fig. 6 is a plan view of the same. Fig. 6^a is a view in detail of the end of my bracket; and Figs. 7, 8, and 9 are respectively 40 a side elevation, a front elevation, and a plan view of another bracket made according to my invention.

Like letters of reference indicate like parts in all the views.

45 Referring particularly to the drawings, A denotes my bracket-arm, having a plate A' of greater thickness than the bracket-arm and located rearward of the same, the bracket-arm having rearwardly-extending shouldered extensions or projections a², terminating in enlarged heads A². The rear portion of the bracket is formed with an orifice a ordinarily punched out of the same and located between the projections a², and an independent plate A' has formed in it a threaded 50 hole (located between openings in the plate

A' for the shouldered portions a²) communicating with the orifice a, in which hole a knob or set-screw B, having a screw-threaded shank b (to bear on the support C) and 60 wrench-holes b', works. The shoulders a² extend out from the edge of the bracket-arm A adjacent to the plate A' in order to engage the openings a¹⁰ of the steadyng-plate A' and to prevent the center of the same from being 65 sprung inward or bent out of its normal position when the knob or set-screw B is manipulated and the shank b thereof pressed against the back bar or support C, which latter is formed with orifices in which the heads 70 A² are entered.

Near the edge of the bracket and adjacent to the recess a⁵ are formed means to engage with the C-shaped spring clamp or rest D, as lateral teeth, prongs, or projections a⁷, which 75 are made by indenting one face of the bracket-arm, and thus causing lips, lugs, or projections to appear on the other side face thereof, and I also provide the recess a⁵ in the top edge of the bracket-arm, whereby the upper 80 face of the said clamp or rest D may preferably be on a level with the supporting edge of the bracket-arm, and a stop may be formed by the recess-shoulder a⁶ for the adjustable 85 clamp or rest.

Other clamp-engaging means than the teeth a⁷ may consist of the humps a⁴, formed by the metal being forced down from the edge or recess of the bracket-arm. The spring clamp or rest D, which is seated with- 90 in the recess a⁵ and movable therein, preferably consists of a flat top face and a slotted bottom portion, thus forming a hollow or grooved clamp or rest, the jaws of which engage the side faces of the bracket-arm and 95 are passed under and cover or inclose and engage the lower portions of the laterally-disposed projections a⁴ or a⁷ on opposite sides of the bracket-arm, whereby the clamp or rest is securely held to a part located adjacent to 100 the same, as the shelf-boards E or other device, which may be rigidly fastened to the clamps D by means of screws F or like devices passed through the orifices d or slots d', formed in the clamp or rest, the screws F 105 thus serving as means to compress the spring jaws and body of the clamp or rest toward each other and to hold the same rigidly against the lateral projections a⁴ or a⁷, whereby the bracket-arm, clamp, or rest and the 110 part engaged therewith may be securely fastened together. The shelves placed upon

the said clamps or rests are preferably separated by means of the vertical lug or lip d^2 , rising from the top face of the said clamp or rest, which thus constitutes a guide and a 5 separating device for the adjacent shelves.

In Figs. 7, 8, and 9 another style of bracket-arm a^{10} is shown, in which the supporting devices, consisting of the shelf-boards E, are secured to the top of the bracket-arm by means 10 of the clamps or rests D, screws F, and the laterally-disposed projections a^7 , formed by indentations made in the opposite faces of the bracket-arm, and the bracket itself is sustained by the primary supporting device, 15 consisting of the walls G^{10} , by means of the clamps D, projections a^7 , and screws F.

What I claim as my invention is—

1. The combination, with a hollow support, having suitable spaced openings in its front 20 wall, of a bracket-arm having shouldered projections on its rear end and an orifice between said projections, a plate of greater width than the thickness of the arm, said plate having openings therein and a screw-threaded hole between the said openings, the 25 projections on the arm passing through the openings in the plate and support and provided with suitable heads, and a set-screw located in said orifice engaging with the 30 screw-threaded hole in the plate and bearing on the support.

2. The combination, with a bracket-arm having a recess formed in its edge, and lateral projections adjacent said recess, of a 35 clamp or rest adapted to be seated within

said recess and movable therein to engage said projections, and having holes to receive screws or other like devices.

3. A bracket-arm having lateral disposed 40 projections formed below and near the upper edge thereof, in combination with a spring-clamp, the top portion of which lies across and in a plane with the edge of the bracket-arm, and the lower parts or jaws of which cover and inclose the said projections, the 45 said spring-clamp having a lug or lip to serve as a separating device for two adjacent articles supported by the said bracket.

4. A bracket-arm having laterally-disposed 50 projections formed near the edge thereof, in combination with a C-shaped spring clamp or rest, the jaws of which are constructed and arranged to engage the lower part of the 55 said laterally-disposed projections on opposite sides of the bracket-arm, the said clamp being also formed with openings extending through the same, a part with which the said clamp or rest may be engaged, and screws to compress the body and jaws of the said clamp toward each other and thereby fasten the 60 said part, bracket-arm and clamp or rest together.

In testimony of the foregoing specification I do hereby sign the same, in the city of New York, county and State of New York, this 3d 65 day of May, 1904.

HENRY FRANCIS KEIL.
